UNITED STATES PATENT OFFICE.

LIZZIE D. CARHART, OF MARION, IOWA.

DARNING-LAST.

SPECIFICATION forming part of Letters Patent No. 432,661, dated July 22, 1890.

Application filed November 20, 1889. Serial No. 330,937. (No model.)

To all whom it may concern:

Be it known that I, LIZZIE D. CARHART, a citizen of the United States, residing at Marion, in the county of Linn and State of Iowa, have invented certain new and useful Improvements in Darning-Lasts; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to darning-lasts for use in darning stockings or other articles, and has for its objects to provide a last possessing flexibility and elasticity, so that it may be easily bent to the shape or curve desired, and by its elasticity will resume its 20 normal shape when the pressure is relieved; also, to provide a last which will prevent contraction of the stocking or other article in darning at the point where the darn is made, and also make a smooth darn, and which can 25 be used without weariness to the hand.

To the accomplishment of the above and such other objects as may hereinafter appear the invention will now be fully described, 30 and afterward referred to in the claims, reference being had to the accompanying drawings, forming part hereof, in which—

Figure 1 is a perspective of a part of a stocking, with portions broken away to represent 35 holes in the same, and darning-threads applied to a portion of one of the holes, the last being inserted in the stocking. Fig. 2 is a plan of the last made of vulcanized or hard rubber. Fig. 3 is an edge view of same, with 40 dotted curved lines representing curves that the last may describe. Fig. 4 is a perspective of a last made of unvulcanized rubber. Fig. 5 is a perspective of same representing it bent into concavo-convexo shape.

45 In the drawings, the letter A designates the last, which may be either flat, concave, or convex in cross-section, although preferably flat, and which will be made of some flexible and elastic material—as, for instance, 50 india-rubber, vulcanized or not—and which

may be of any suitable thickness. A good thickness is one-sixteenth of an inch, and a good length is three or eight inches long by two or four wide.

While the foregoing dimensions are considered to be the best, still I do not limit myself thereto, as other dimensions may be followed, and the size made to depend on the particular use to be made of the last. If the last is of vulcanized or hard rubber, it 55 may be one-fortieth of an inch thick. The preferred form is an irregular oval shape, of which an illustration is given in the drawings, and one which will correspond more or less to the shape of a stocking, although the 60 shape may be varied without departing from other features of my invention.

The form illustrated in the accompanying drawings adapts the last to the shape of the foot and heel of different sizes of stockings. 70

The last may be either molded or cut into the desired shape or otherwise formed. It will be understood that when concave or convex the construction is to be such that the flexibility of the last and its capability of 75 change to different surface curvatures are not to be destroyed, for if that were done one main object of the invention would be defeated.

In use the last is inserted into the leg or foot of a stocking B, or beneath the article 80 to be darned, and under the hole or rent to be closed, and then, with the last either in its normal condition or bent or curved to the extent desired, the darning-threads C are applied, as usual, to close the rent or hole; but 85 owing to the flexibility of the last the stocking or other article being darned is distended to the extent desired, while the elasticity of the last will hold the portions of the article under sufficient tension to enable a smooth 90 darn to be made.

Owing to the shape, flexibility, and elasticity of the last it can be held and manipulated by the hand without fatigue.

Having described my invention and set 95 forth its merits, what I claim is—

1. A darning-last composed of a suitable flexible elastic material constructed of a sectional thickness less than its length or breadth, and which will allow it to be bent 100

by hand to assume different surface curvatures, substantially as and for the purposes set forth.

2. A darning - last substantially flat in cross-section and composed of a suitable flexible elastic material constructed of a sectional thickness which will allow it to be bent by hand to assume different surface

curvatures, substantially as and for the purposes set forth.

In testimony whereof I affix my signature in presence of two witnesses.

LIZZIE D. CARHART.
